CLAIM

The ornamental design for a transmitter for wireless microphone, as shown and described.

DESCRIPTION

FIG. 1 is a top, front, right side perspective view of a transmitter for wireless microphone, showing my design.

FIG. 2 is a bottom, rear, left side perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the transmitter for wireless microphone that form no part of the claimed design.

1 Claim, 8 Drawing Sheets
